UNITED STATES PATENT OFFICE.

FREDERICK C. LUFF, OF CLEVELAND, OHIO.

DESIGN FOR A SPRINKLING-BULB.

SPECIFICATION forming part of Design No. 35,335, dated November 26, 1901;

Application filed October 19, 1901. Serial No. 79,306. Term of patent 7 years.

To all whom it may concern:

Be it known that I, FREDERICK C. LUFF, a citizen of the United States of America, residing at Cleveland, in the county of Cuyahoga and State of Ohio, have invented and produced a certain new and original Design for Sprinkling-Bulbs, of which the following is a specification, reference being had to the accompanying drawings, in which—

Figure 1 represents a perspective view, Fig. 2 a plan view, Fig. 3 a view of the side edge, and Fig. 4 a view of the front edge, of my sprinkling-bulb.

My design consists of a bulb of flattened shape, its upper and lower faces *a* being slightly convex and its front edge *b* substantially semicircular in shape both longitudinally and transversely. The front rounded semicircular edge is provided with several rows of small holes *c*, and the side edges *d* of

the bulb incline toward each other and connect with a cylindrical stem *e*, these side edges being rounded semicircularly to merge nicely into the blunt rounded front edge and into the cylindrical form of the stem, as 25 shown. The outer or rear end of the stem is provided with an annular bead *f*.

Having thus fully described my invention, what I claim as new, and desire to secure by Letters Patent, is—

The design for a sprinkling-bulb substantially as herein shown and described.

In testimony whereof I hereunto affix my signature, in the presence of two witnesses, this 11th day of October, 1901.

FREDERICK C. LUFF.

Witnesses:

R. J. WARDNER,
FREDERICK C. CHANDLERS.
